UNITED STATES PATENT OFFICE.

ALBERT B. PHISTER, OF FORT THOMAS, KENTUCKY, ASSIGNEE TO THE PHISTER MANUFACTURING COMPANY, OF CINCINNATI, OHIO, A CORPORATION OF OHIO.

FIRE EXTINGUISHER.

Application filed June 16, 1919. Serial No. 304,362

To all whom it may concern:

Be it known that I, ALBERT B. PHISTER, a citizen of the United States, and a resident of Fort Thomas, in the county of Campbell 5 and State of Kentucky, have invented certain new and useful Improvements in Fire-Extinguishers, of which the following is a specification.

My invention relates to chemical fire-extinguishers. Its object is to provide devices 10 of this character which will be of ample capacity yet readily portable and convenient to operate, and which will be more durable and dependable.

15 My invention consists in the combination of parts and in the details of construction and arrangement of parts as will hereinafter be more fully described and claimed.

In the drawings:

20 Fig. 1 is a front elevation of a device embodying my invention;

Fig. 2 is a side elevation of the same;

Fig. 3 is an enlarged plan view of the same;

25 Fig. 4 is a cross-section of the upper part of the device on a vertical plane corresponding to the line 4—4 of Fig. 3;

Fig. 5 is a cross-section on a vertical plane corresponding to the line 5—5 of Fig. 3, 30 showing the upper and lower parts of the device but represented as with middle parts broken away and omitted for lack of space;

Fig. 6 is a cross-section of an upper part of the device on a vertical plane corresponding to the line 6—6 of Fig. 3; and

Fig. 7 is a similar section on a plane corresponding to the line 7—7 of Fig. 3.

The device which I disclose herein as an example of my invention includes a tank 1 40 which is made up of an upright tubular shell 2 having an upper head 3 and a lower head 4 which are closely fitted in the respective ends of the shell 2 and fixed thereto in an air-tight manner, as by soldering or welding. About halfway in from the shell 2 to the centers of the respective heads 3 and 4 on their lower and upper sides, respectively, inside the tank 1 are annular flanges 5 and 6 preferably integral with the respective 45 heads and concentric with the shell 2. An inner tubular shell 7 has its upper and lower ends fitted in these flanges 5 and 6 respectively and made air-tight therewith as by soldering or welding. The lower head 55 4 has the depending rim 8 with the base-

flange 9 extending out all around from its lower edge. This elevates the main part of the lower head 4 and in the center thereof is the depending cup 10 opening upwardly. The rim 8, flange 9 and this cup 10 60 are all preferably integral with the lower head 4; these parts being conveniently made in the form of a casting. The upper head 3 has in its center the upstanding hub 11 which has the concentric socket 12 opening 65 from its top and threaded for some distance down from the top. In the center of the bottom of this socket 12 the head 3 has an opening down through it into which fits tightly the upper end of the tubular pump casing 70 13, the lower end of which fits tightly inside the central cup 10 of the lower head 4. This pump casing is made air-tight with the heads by soldering or welding or the like the same as the shells 2 and 7. 75

This construction with successive concentric tubes fixed to the upper and lower heads is very substantial; and it will be seen that it provides an air-tight annular compartment 14 enclosed between the outer 80 tank shell 2 and the shell 7 and upper and lower heads 3 and 4; another annular compartment 15 between the inner shell 7, pump casing 13 and upper and lower heads; and, centrally, the pump compartment within the 85 casing 13, closed at the bottom by the cup 10 and opening upwardly through the socket 12 of the hub 11 in the head 3.

The outermost compartment 14 is for liquid; the next compartment 15 is for compressed air; and the pump that comprises the casing 13 in the center is for compressing the air into the middle compartment 15. 90

This pump comprises the tubular plunger-rod 16 which passes down into the pump 95 casing 13 through the hub 11 at the top. This tubular rod 16 is of diameter considerably less than that of the inside of the pump casing 13 so that a considerable annular space 17 is left around the rod 16 inside the casing 13. The internally threaded socket 12 has screwed into it the bushing 18 which fits closely around the plunger-rod 16 with an upper hexagonal part for conveniently turning it. A packing washer 19 100 is fixed against the bottom of this bushing 18 by means of a ring 20 fastened to the bushing 18 by screws 21 passing up through the ring 20 and washer 19 into the bushing. This washer 19 is made of some closely 105

110

2 clinging flexible material such as rubber, or preferably leather, and its radial cross-section is angular, having a horizontal outward extending part that comes between the ring 20 and the bushing and inner depending part that fits tightly around the smooth outer surface of the tubular plunger-rod 16. The ring 20 has an inwardly projected annular flange 22 at its bottom coming under the washer 19 close to the plunger-rod 16. This ring 20 thus disposed is designed to reinforce and protect the flexible packing washer 19. It does not entirely fill the lower unthreaded part of the socket 12 but leaves ample space therearound which communicates freely with the annular space 17 in the pump casing around the plunger-rod.

The lower end of this tubular plunger-rod 16 has the plunger 23 fixed to it by having a reduced upper end part 24 of the plunger fitting snugly in its end and suitably secured thereto in an air-tight manner as by soldering or welding. Immediately below this there is the radially projected annular bead 25 on the plunger 23, and extending from the center of the bottom of the plunger is the neck 26 which is externally threaded and has screwed on it the nut 27 which holds up against the bottom of the plunger 23, around the neck 26, the cup-washer 28 with its sides extending up and surrounding the plunger 23 with their upper edges coming close under the bead 25. This bead 25, like the ring 20, is for the purpose of protecting the adjacent flexible washer and leaves a considerable annular space around it next to the pump casing wall; the cup-washer 28 fitting tightly out against said wall. This plunger 23 has a central opening up through it from the lower end of its neck 26 up into the interior of the tubular plunger-rod 16. This opening comprises the lowermost internally threaded part with a port 26' at one side and the upper reduced part 29 with an annular shoulder forming a valve seat 30 between these two parts; and the lower threaded part has screwed into it the plug 31 which has in its lower end a transverse slot for engagement of a screw driver or the like and has in its upper end the central opening receiving the lower end of the stem of the check valve 32 which seats upwardly against the seat 30, preferably having a facing 33 of rubber or the like to directly engage with the seat 30 and being pressed up by a spring 34 coiled around its stem between the plug 31 and the bottom of the valve. The upper head 3 in addition to the central hub 11 has the shifting-valve body 35 at one side and joined to the hub by a short radial rib. Directly adjoining this body 35 is the filling neck 36 which has its opening down into the liquid compartment 14 inter-

nally threaded and closed by a plug 37 screwed therein.

A check-valve socket extends down into the rib and has, leading from its body downwardly and then radially into the hub 70 socket 12, a port 38. At the junction of the port 38 and check-valve socket an annular shoulder forms the valve seat 39 down upon which seats the check valve 40 with a rubber or leather facing 41 against the seat 39 75 and having its stem extending up into the central opening of the plug 42 that is screwed down into the internally threaded upper part of the check-valve socket and has a slot in its upper end to receive a screw driver or the like. This valve 40 may be depended upon to seat with the help of gravity and ordinarily will not require any spring like the check valve 32 in the plunger 23, to which it is otherwise very similar. 80

The valve body 35 has the downwardly tapered interior receiving the correspondingly tapered plug 43 which has a central opening from top to bottom down through which passes a stud 44 which is screwed down into the head 3 at the center of the bottom of the interior of this valve body and which has screwed on to its upper end a nut 45 with a washer 46 keyed on between it and the top of the valve plug to thereby hold the plug tightly down in the body. This top of the plug has a radially extended rim 47 most of the way around but discontinued at one side to leave a flat 48 (Fig. 3) 90 and has extending radially from another side a short handle 49 for turning the plug. A short port 50 leads from the check-valve socket above the check valve 40 into the interior of the shifting-valve body. At the opposite side of this valve body against the filling neck 37 is a short boss 51 in which a port 52 is formed leading from the inferior of the shifting-valve body horizontally to a port 53 that leads down through the head 3 into the liquid compartment 14. The horizontal port 52 is preferably bored from the outer end of the boss 51 and then its outer part closed by a filling 54. 100

The head 3 also has the air-valve body 55 over near one side and to the rear of the shifting valve; and has the outlet-valve body 56 over to the other side at the rear. These valve bodies 55 and 56 are aligned across the head and are elongated in this direction to receive their valve members horizontally. 115 In the air-valve body is the horizontal valve chamber 57 from the outer end of which a port 58 leads horizontally to another port 59 (Fig. 4) that inclines downwardly and inwardly through the bottom of the head 3 120 into the air compartment 15. Like the port 52, the port 58 is preferably bored from the outer end of the body 55 into the chamber 57 and then has its outer end closed by a filling 60. A rib extends from the air-valve 130

body 55 forward to the shifting-valve body 35; containing the port 61 that leads from the air-valve chamber 57 into the interior of the shifting-valve body.

5 The shifting-valve plug 43 has a segmental slot 62 extending a little more than one-quarter way around it in such relation to the flat 48 at the top of the plug that when this flat 48 is next to the filling neck this slot 10 62 connects the port 52 with the port 61 to the exclusion of the port 50; but if turned about one-quarter way around, the slot 62 connects the port 50 with the port 61 to the exclusion of the port 52.

15 The air valve 63 is a pin with a tapered end fitting in a conical seat 64 where the port 58 leads from the chamber 57, and joins its rod 65 of somewhat greater cross-section over past the port 61; this rod fitting snugly in the chamber 57, and the body 55 having a stuffing-box 66 containing packing compressed around the rod 65 by the gland 67 which is screwed into the stuffing-box in a usual manner.

25 The outlet-valve body 56 has its interior opening tapered from its outer end inwardly, receiving the correspondingly tapered outlet-valve plug 68, having fixed to its end the handle 69 which is stopped in depending position by engaging the side of the tank as shown, and extending through the inner end of the body 56 with an externally threaded neck 70 on which is a keyed washer 30 and a lock nut 72, holding the tapered plug 68 tightly in the body 56 in a usual manner.

The end of the rod 65, which is coaxial with the plug 68 has a flat bit 73 on its end, and there is a transverse slot 74 in the neck 40 70 adjacent to the end of the rod; this slot receiving the flat bit 73, which thus causes the air-valve rod 65 to turn with the outlet-valve plug 68. Next to the end part 73 the air-valve rod 65 has the external threads 75 45 and a casing 76 fits down over the just described parts at the inner end of the outlet-valve body 56 and is suitably fixed to said body and has a thickened end part through which the threads 75 of the air-valve rod 65 are screwed; whereby this casing 76 acts as a fixed nut for the screw 60 whereby turning thereof along with the outlet-valve plug forces the air valve 63 toward or from its seat 64. The key 74 is 55 considerably shorter than its space in the slots so that there can be this lengthwise movement of the air valve without any corresponding lengthwise movement of the tapered outlet-valve plug.

60 The outlet-valve body 56 has the port 77 leading from its tapered interior down through the head 3 and an outlet tube 78 has its upper end screwed into the head 3 in the lower end of this port 77; this outlet tube 78 extending down very close to the

lower head 4 or bottom of the liquid compartment 14. Another port 79 leads transversely through one side of the body 56 with a nipple 80 extending forwardly from its outer end; and over the front end of this 70 nipple is slipped the end of the discharge hose 81, which is preferably made of metal, coiled down around the outside of the tank 1, having its nozzle 82 held by a spring clip 83 fastened on the side of the lower-head 75 flange 8 close to the base flange 9.

The outlet-valve plug 68 has the segmental slot 84 extending a little over quarter way around and so positioned relative to the connection with the air valve 63 that when this air valve 63 is seated this slot 84 will be at the lower rear side of the plug over the lower port 77; and the opening of the outlet valve is effected by turning it forwardly or to the left as indicated by the arrow in Fig. 6 so that a three-quarter turn is needed to bring this slot 84 around where it will connect the lower port 77 with the port 79 to the hose 81. The pitch of the threads 75 is enough so that this three-quarter turn will sufficiently open the air valve 63 and at the same time this pitch of these threads 75 is kept moderate enough so that a very strong pressure may be brought to bear in seating the air valve 63 by the reverse three-quarter turn of the plug 68 in closing the outlet valve.

The pump plunger-rod 16 has a handle formed by a smaller tube 85 passed transversely through openings in the walls of the upper end part of the rod 16 and fixed therein by means of a bolt 86 passing through both tubes 85 and 16 at right angles to them. 100

The apparatus has a handle 87 that comprises the main transverse part with the side members 88 curving downwardly and forwardly with their lower end parts fixed to lugs 89 at opposite sides of the rear of the upper head 3. This handle 87 serves for hanging the apparatus up and also for carrying it.

The upper head 3 like the lower head 4 is preferably a casting with not only the filling neck flange 5 and central hub 11 but the 115 filling neck and the three valve bodies and connecting ribs and handle lugs formed integrally therewith.

The device is also preferably provided with a pressure gauge 90 at the front with a nipple 91 centrally in its back, screwed into a boss 92 on the front of the hub 11 and communicating with a port 93 that leads down through the head 3 into the air compartment 15. The head 3 preferably has the integral guard projections 94 at the opposite sides of the gauge 90 for protecting the gauge. 120 125

Suitable liquid is poured in the liquid compartment 14 through the filling neck 120

4
while the plug 37 is removed; it being understood that the liquid should include such elements as will, in contact with air, and upon emerging from the nozzle 82 onto the fire, act upon the fire in such a way as to smother it, as is well known in the art.

When this plug 37 is removed it permits the shifting-valve plug to be turned through the necessary angle to connect the ports 50 and 61. This at the same time closes the port 52 so that there will be no leakage from the air compartment 15 into the now opened liquid compartment. And it permits air to now be forced by the pump 15 through the port 50, slot 62, port 61, chamber 57 and ports 58 and 59 into the air compartment 15 if the outlet-valve plug has been turned so as to open the air valve 63. It is, of course, permissible to open this outlet valve now because the port 52 is closed and this opening of the outlet valve is only an opening additional to that of the filling neck.

The pumping is done by moving the tubular plunger-rod 16 and its attached plunger and other parts up and down in the casing 13. In working this pump the apparatus is held stationary by the feet of the operator bearing on the base flange 9. The plunger check valve yields on the upward stroke and admits atmospheric air under the plunger which on the downward stroke will be forced past the cup washer 28 into the compartment 17 around the plunger-rod 16 in the casing 13. Then at the next upward stroke the expansion of the cup washer 28 will cause this air to be forced from the compartment 17 through the lower part of the hub socket 12 and the port 38, raising the check valve 40 and passing through the port 50 and the other passages by way of the air valve into the air compartment 15 as just before described. The check valve 40 of course prevents back-flow as the pump 45 plunger passes downward. This pump, admitting air through its hollow plunger-rod past a check valve in the plunger on the upward stroke and then admitting this same air past its cup washer on the downward stroke, thus has a two-stage operation. It is thus possible to manually raise the air to a very high pressure in the tank 15. A pump constructed in this way has been operated by one man to compress the air to a pressure 55 of about two hundred pounds.

By having the air and liquid compartments separate it is possible to have a very practical air valve which will not be corroded as when it is exposed to the liquid. 60 This permits the air under high pressure to be retained for an indefinite period. This permits of the storage of a relatively large quantity of air without having the apparatus of such bulk or weight as to be unwieldy.

When the liquid compartment 14 has been filled with the proper liquid and sufficient air has been compressed into the air compartment, the outlet valve is closed; which also closes the air valve. It is now permissible to turn the shifting valve back to its normal position where it will connect the air valve with the liquid compartment and will permit the plug 37 to be screwed into the filling neck. This insertion of the plug 37 is prevented with the shifting valve out of position because of the extension of the flange 47 on the shifting-valve plug. This insures that the apparatus will not be left with the connection cut off between the air compartment and the liquid compartment, in which condition it would not operate even though the outlet and air valves were open. The person opening the device will not readily forget to insert the plug 37 and is compelled to properly open the shifting valve before doing this.

To use the apparatus when thus properly prepared it is necessary only to carry it to the fire, unwinding the hose 81 while doing so, and then with the hose directed toward the fire, swing the handle 69 through its three-quarter turn which will simultaneously admit the compressed air onto the liquid and open the outlet through the hose for commingled air and chemicals to escape onto the fire.

While certain constructional details are deemed preferable in connection with my invention, and I have shown and described these rather specifically in elucidating the construction and use of my invention, as is required, I do not wish to be understood as being limited to such precise showing and description, but having thus fully described my invention, what I claim as new and desire to secure by Letters Patent is:

1. In a fire-extinguisher, a liquid compartment, an air compartment, air-forcing means, an air valve communicating with said air compartment, a shifting valve to open communication either between said air valve and said liquid compartment to the exclusion of said air-forcing means or between said air valve and said air-forcing means to the exclusion of said liquid compartment, and means operated simultaneously with said air valve for controlling discharge of liquid from said liquid compartment.

2. In a fire-extinguisher, a liquid compartment, an air compartment, air-forcing means, an air valve communicating with said air compartment, a shifting valve to open communication either between said air valve and said liquid compartment to the exclusion of said air-forcing means or between said air valve and said air-forcing means to the exclusion of said liquid compartment, said liquid compartment having a filling opening, a closure for said opening, and

- means whereby said closure is prevented from closing said opening except when said shifting valve opens communication between said air-valve and said liquid compartment, and means for controlling discharge of liquid from said liquid compartment.
3. In a fire-extinguisher, a liquid compartment, an air compartment, air-forcing means, an air valve communicating with said air compartment, a shifting valve to open communication either between said air valve and said liquid compartment to the exclusion of said air-forcing means or between said air valve and said air-forcing means to the exclusion of said liquid compartment, said liquid compartment having a filling opening, a closure for said opening, and means whereby said closure is prevented from closing said opening except when said shifting valve opens communication between said air valve and said liquid compartment, and means operated simultaneously with said air valve for controlling discharge of liquid from said liquid compartment.
- 25 4. In a fire-extinguisher, a liquid compartment, an air compartment, air-forcing means, an air valve for admitting air under pressure from said air compartment directly into contact with a liquid in said liquid compartment for extinguishing operation but excluding such air from said liquid compartment between operations, whereby said air valve is relieved from forced exposure to said liquid between operations, a shifting valve to open communication either between said air valve and said liquid compartment to the exclusion of said air-forcing means or between said air valve and said air-forcing means to the exclusion of said liquid compartment, and means operated simultaneously with said air valve for controlling discharge of commingled liquid and air from said compartment.
- 35 5. In a fire-extinguisher, a liquid compartment, an air compartment, air-forcing means, an air valve for admitting air under pressure from said air compartment directly into contact with a liquid in said liquid compartment for extinguishing operation but excluding such air from said liquid compartment between operations, whereby said air valve is relieved from forced exposure to said liquid between operations, a shifting valve to open communication either between said air valve and said liquid compartment to the exclusion of said air-forcing means or between said air valve and said air-forcing means to the exclusion of said liquid compartment, said liquid compartment having a filling opening, a closure for said opening, and means whereby said closure is prevented from closing said opening except when said shifting valve opens communication between said air valve and said liquid compartment, and means for controlling discharge of commingled liquid and air from said liquid compartment.
- 40 6. In a fire-extinguisher, a liquid compartment, an air compartment, air-forcing means, an air valve for admitting air under pressure from said air compartment directly into contact with a liquid in said liquid compartment for extinguishing operation but excluding such air from said liquid compartment between operations, whereby said air valve is relieved from forced exposure to said liquid between operations, a shifting valve to open communication either between said air valve and said liquid compartment to the exclusion of said air-forcing means or between said air valve and said air-forcing means to the exclusion of said liquid compartment, and means operated simultaneously with said air valve for controlling discharge of commingled liquid and air from said liquid compartment.
- 45 7. In a fire-extinguisher, an outer shell, an upper head and a lower head in said shell, an inner shell extending from one of said heads to the other inside said outer shell, these shells being closed by said heads, a pump casing inside said inner shell, closed at one end by said lower head and opening through said upper head, pumping means in said casing, air-outlet means in said upper head from said casing into said inner shell and from said inner shell into said outer shell, a check valve in this means opening from said pump casing, and air-and-liquid-outlet means in said upper head, leading from said outer shell.
- 50 8. In a fire-extinguisher, an outer shell, an upper head and a lower head in said shell, an inner shell extending from one of said heads to the other inside said outer shell, these shells being closed by said heads, a pump casing inside said inner shell, closed at one end by said lower head and opening through said upper head, pumping means in said casing, said upper head comprising a shifting-valve body and an air-valve body, and having a port from said pump casing into said shifting-valve body with a check valve opening from said pump casing, and a port from said shifting valve body into said air-valve body and ports from said air-valve body and said shifting-valve body into said inner shell and said outer shell, respectively, a shifting-valve element in said shifting-valve body to connect either said pump-casing port or said outer-shell port with said air-valve port to the exclusion of the other port, an air valve element in said air-

- 6
- valve body to close said inner-casing port, and air-and-liquid-outlet means in said upper head, leading from said outer shell.
9. In a fire-extinguisher, an outer shell, 5 an upper head and a lower head in said shell, an inner shell extending from one of said heads to the other inside said outer shell, these shells being closed by said heads, a pump casing inside said inner shell, closed 10 at one end by said lower head and opening through said upper head, pumping means in said casing, said upper head comprising a shifting-valve body and an air-valve body, and having a port from said pump casing 15 into said shifting-valve body with a check valve opening from said pump casing, and a port from said shifting valve body into said air-valve body and ports from said air-valve body and said shifting-valve body into said 20 inner shell and said outer shell, respectively, a shifting-valve element in said shifting-valve body to connect either said pump-casing port or said outer-shell port with said air-valve port to the exclusion of the other 25 port, an air valve element in said air-valve body to close said inner-casing port, said upper head comprising a filling neck adjacent to said shifting-valve body, and a closure for said neck, said shifting-valve element 30 having means obstructing said closure when connecting said pump-casing port and said air-valve port, and air-and-liquid-outlet means in said upper head, leading from said outer shell.
- 35 10. In a fire-extinguisher, an outer shell, an upper head and a lower head in said shell, an inner shell extending from one of said heads to the other inside said outer shell, these shells being closed by said heads, a 40 pump casing inside said inner shell, closed at one end by said lower head and opening through said upper head, pumping means in said casing, said upper head comprising a shifting-valve body and an air-valve body, 45 and having a port from said pump casing into said shifting-valve body with a check valve opening from said pump casing, and a port from said shifting-valve body into said air-valve body and ports from said air- 50 valve body and said shifting-valve body into said inner shell and said outer shell, respectively, a shifting-valve element in said shifting-valve body to connect either said pump casing port or said outer-shell port with said air-valve port to the exclusion of the other 55 port, an air valve element in said air-valve body to close said inner-casing port, said upper head comprising an outlet valve body with a port from said outer shell, a 60 screw to open said air-valve element, a rotary valve plug in said outlet-valve body coaxial with said screw, and an operative connection between said plug and said screw whereby said plug opens said air valve when 65 it opens said port of said outlet-valve body.
11. In a fire-extinguisher, an outer shell, an upper head and a lower head in said shell, an inner shell extending from one of said heads to the other inside said outer shell, these shells being closed by said heads, 70 a pump casing inside said inner shell, closed at one end by said lower head and opening through said upper head, pumping means in said casing, said upper head comprising a shifting-valve body and an air-valve body, 75 and having a port from said pump casing into said shifting-valve body with a check valve opening from said pump casing, and a port from said shifting-valve body into said air-valve body and ports from said air- 80 valve body and said shifting-valve body into said inner shell and said outer shell, respectively, a shifting-valve element in said shifting-valve body to connect either said pump casing port or said outer-shell port with said air-valve port to the exclusion of the other 85 port, an air-valve element in said air-valve body to close said inner-casing port, said upper head comprising a filling neck adjacent to said shifting-valve body, a closure 90 for said neck, said shifting-valve element having means obstructing said closure when connecting said pump-casing port and said air-valve port, said upper head comprising an outlet valve body with a port from said outer shell, a screw to open said air-valve element, a rotary valve plug in said outlet-valve body coaxial with said screw, and an operative connection between said plug and said screw whereby said plug opens said air valve when it opens said port of said outlet-valve body.
12. In a fire-extinguisher, an outer shell, an upper head and a lower head in said shell, an inner shell extending from one of said heads to the other inside said outer shell, these shells being closed by said heads, 105 a pump casing inside said inner shell, closed at one end by said lower head and opening through said upper head, a plunger sliding in said casing, a plunger rod on said plunger extending out of the other end of said casing and having an air space around it in said casing and an air inlet passage to said plunger inside said plunger rod, a check 110 valve opening from said air inlet passage to said space between said plunger and said closed end, a check valve opening from this space to said space around said plunger rod, air-outlet means in said upper head from said casing into said inner shell and from said inner shell into said outer shell, a check valve in this means opening from said pump casing, and air-and-liquid-outlet means in said upper head, leading from said outer shell.
13. In a fire-extinguisher, an outer shell, an upper head and a lower head in said shell, an inner shell extending from one of said heads to the other inside said outer shell,

these shells being closed by said heads, a pump casing inside said inner shell, closed at one end by said lower head and opening through said upper head, a plunger sliding in said casing, a plunger rod on said plunger extending out of the other end of said casing and having an air space around it in said casing and an air inlet passage to said plunger inside said plunger rod, a check valve opening from said air inlet passage to said space between said plunger and said closed end, a check valve opening from this space to said space around said plunger rod, said upper head comprising a shifting-valve body and an air-valve body, and having a port from said pump casing into said shifting-valve body with a check valve opening from said pump casing, and a port from said shifting valve body into said air-valve body 20 and ports from said air-valve body and said shifting-valve body into said inner shell and said outer shell, respectively, a shifting-valve element in said shifting-valve body to connect either said pump-casing port 25 or said outer-shell port with said air-valve port to the exclusion of the other port, an air valve element in said air-valve body to close said inner-casing port, and air-and-liquid-outlet means in said upper head, 30 leading from said outer shell.

14. In a fire-extinguisher, an outer shell, an upper head and a lower head in said shell, an inner shell extending from one of said heads to the other inside said outer shell, these shells being closed by said heads, a pump casing inside said inner shell, closed at one end by said lower head and opening through said upper head, a plunger sliding in said casing, a plunger rod on said plunger extending out of the other end of said casing and having an air space around it in said casing and an air inlet passage to said plunger inside said plunger rod, a check valve opening from said air inlet passage to said space between said plunger and said closed end, a check valve opening from this space to said space around said plunger rod, said upper head comprising a shifting-valve body and an air-valve body, and having a port from said pump casing into said shifting-valve body with a check valve opening from said pump casing, and a port from said shifting valve body into said air-valve body and ports from said air-valve body and said shifting-valve body into said inner shell and said outer shell, respectively, a shifting-valve element in said shifting-valve body to connect either said pump-casing port or said outer-shell port with said air-valve port to the exclusion of the other port, an air valve element in said air-valve body to close said inner-casing port, said upper head comprising an outlet valve body with a port from said outer shell, a screw to open said air-valve element, a rotary valve plug in said outlet-valve body coaxial with said screw, and an operative connection between said plug and said screw whereby said plug opens said air valve when it opens said port of said outlet-valve body.

45 15. In a fire-extinguisher, an outer shell, an upper head and a lower head in said shell, an inner shell extending from one of said heads to the other inside said outer shell, these shells being closed by said heads, a pump casing inside said inner shell, closed at one end by said lower head and opening through said upper head, a plunger sliding in said casing, a plunger rod on said plunger extending out of the other end of said casing and having an air space around it in said casing and an air inlet passage to said plunger inside said plunger rod, a check valve opening from said air inlet passage to said space between said plunger and said closed end, a check valve opening from this space to said space around said plunger rod, said upper head comprising a shifting-valve body and an air-valve body, and having a port from said pump casing into said shifting-valve body with a check valve opening from said pump casing, and a port from said shifting valve body into said air-valve body and ports from said air-valve body and said shifting-valve body into said inner shell and said outer shell, respectively, a shifting-valve element in said shifting-valve body to connect either said pump-casing port or said outer-shell port with said air-valve port to the exclusion of the other port, an air valve element in said air-valve body to close said inner-casing port, said upper head comprising a filling neck adjacent to said shifting-valve body, and a closure for said neck, said shifting-valve element having means ob-

structing said closure when connecting said pump-casing port and said air-valve port, and air-and-liquid-outlet means in said upper head, leading from said outer shell.

16. In a fire-extinguisher, an outer shell, 70 an upper head and a lower head in said shell, an inner shell extending from one of said heads to the other inside said outer shell, these shells being closed by said heads, a pump casing inside said inner shell, closed at one end by said lower head and opening through said upper head, a plunger sliding in said casing, a plunger rod on said plunger extending out of the other end of said casing and having an air space around it in 75 said casing and an air inlet passage to said plunger inside said plunger rod, a check valve opening from said air inlet passage to said space between said plunger and said closed end, a check valve opening from this space to said space around said plunger rod, said upper head comprising a shifting-valve body and an air-valve body, and having a port from said pump casing into said shifting-valve body with a check valve opening 80 from said pump casing, and a port from said shifting valve body into said air-valve body and ports from said air-valve body and said shifting-valve body into said inner shell and said outer shell, respectively, a shifting-valve element in said shifting-valve body to connect either said pump-casing port or said outer-shell port with said air-valve port to the exclusion of the other port, an air valve element in said air-valve body to close said inner-casing port, said upper head comprising 85 an outlet valve body with a port from said outer shell, a screw to open said air-valve element, a rotary valve plug in said outlet-valve body coaxial with said screw, and an operative connection between said plug and said screw whereby said plug opens said air valve when it opens said port of said outlet-valve body.

17. In a fire-extinguisher, an outer shell, 110 an upper head and a lower head in said shell, an inner shell extending from one of said heads to the other inside said outer shell, these shells being closed by said heads, a pump casing inside said inner shell, 115 closed at one end by said lower head and opening through said upper head, a plunger sliding in said casing, a plunger rod on said plunger extending out of the other end of said casing and having an air space around it in said casing and an air inlet passage to said plunger inside said plunger rod, a check valve opening from said air inlet passage to said space between said plunger and said closed end, a check valve 120 opening from this space to said space around said plunger rod, said upper head comprising a shifting-valve body and an air-valve body, and having a port from said pump casing into said shifting-valve body with a check valve 125 opening from said pump casing, and a port from said shifting valve body into said air-valve body and ports from said air-valve body and said shifting-valve body into said inner shell and said outer shell, respectively, a shifting-valve element in said shifting-valve body to connect either said pump-casing port or said outer-shell port with said air-valve port to the exclusion of the other port, an air valve element in said air-valve body to close said inner-casing port, said upper head comprising a filling neck adjacent to said shifting-valve body, and a closure for said neck, said shifting-valve element having means ob-

ing-valve body with a check valve opening from said pump casing, and a port from said shifting valve body into said air-valve body and ports from said air-valve body and said shifting-valve body into said inner shell and said outer shell, respectively, a shifting-valve element in said shifting-valve body to connect either said pump-casing port or said outer-shell port with 10 said air-valve port to the exclusion of the other port, an air valve element in said air valve body to close said inner-casing port, said upper head comprising a filling neck adjacent to said shifting-valve body, 15 a closure for said neck, said shifting-valve element having means obstructing said closure when connecting said pump-casing port and said air-valve port, said upper head comprising an outlet valve body with 20 a port from said outer shell, a screw to open said air-valve element, a rotary valve plug in said outlet valve body coaxial with said screw, and an operative connection between said plug and said screw whereby 25 said plug opens said air valve when it opens said port of said outlet-valve body.

17. In a fire extinguisher, a tank to hold a fire extinguishing liquid, a tank to hold compressed air to expel the liquid, and a 30 pump to pump air into the compressed air tank, said tanks and the casing of said pump having an upper single end enclosing piece for the respective tanks and pump casing and a lower single and enclosing piece for the respective tanks and pump, 35

substantially as set forth and for the purposes specified.

18. In a fire-extinguisher, a tank to hold a fire-extinguishing liquid and a tank to hold compressed air to expel the liquid, a 40 pump to pump air into the compressed-air tank, and an end for both tanks and said air pump, comprising an extension forming a foot-hold to hold said extinguisher while operating said pump, and formed of a 45 single piece.

19. In a fire-extinguisher, a tank to hold a fire-extinguishing liquid, a tank to hold compressed air to expel the liquid, a pump to pump air into the compressed-air tank, a shifting valve either connecting the liquid tank and pump or connecting the two tanks, an air valve cutting said shifting valve off from the air tank, and a filling plug for the liquid tank, said shifting valve being of such shape that said liquid-tank filling plug can not be placed in its proper position unless said shifting valve is in such position that when said air valve is opened air will 55 flow from the air tank through said shifting valve into the liquid tank instead of through said shifting valve into said pump.

20. A tank end, a portion of a pump end, stop cock body, air valve body and shifting valve body, all formed of a single piece.

ALBERT B. PHISTER.
